Patented Sept. 6, 1966

205,665

FURNITURE LEG

George H. Nelson, New York, N.Y., assignor to Herman Miller, Inc., Zeeland, Mich., a corporation of Michigan

Filed Apr. 12, 1965, Ser. No. 84,749

Term of patent 14 years

(Cl. D33—1)

Fig. 1

Fig. 2

Fig. 3

FIG. 4

FIG. 5

FIG. 11

FIG. 6

FIG. 8

FIG. 10

FIG. 7

FIG. 9

FIG. 12

FIG. 1 is a perspective view of the side and one end of my novel design;

FIG. 2 is an end view of the furniture leg illustrated in FIG. 1;

FIG. 3 is a side elevational view of the furniture leg illustrated in FIG. 1;

FIG. 4 is a perspective sectional view of the end portion of the arms of the furniture leg;

FIG. 5 is a fragmentary, perspective, sectional view taken from the general direction of and including the area encompassed by the bracket A of FIG. 3;

FIG. 6 is a sectional view taken on plane VI—VI of FIG. 3;

FIG. 7 is a sectional view taken on plane VII—VII of FIG. 3;

FIG. 8 is a sectional view taken on plane VIII—VIII of FIG. 3;

FIG. 9 is a sectional view taken on plane IX—IX of FIG. 3;

FIG. 10 is a sectional view taken on plane X—X of FIG. 3;

FIG. 11 is a sectional view taken on plane XI—XI of FIG. 3; and

FIG. 12 is a sectional view taken on plane XII—XII of FIG. 3.

The opposite end of the leg to that illustrated in FIG. 2 has a mirror image appearance to that end shown in FIG. 2. The opposite side of the leg to that illustrated in FIG. 3 has a mirror image appearance to that shown in FIG. 3.

I claim:

The ornamental design for a furniture leg, substantially as shown and described.
